D L Miller

^{inventor}
Simeon Taylor

United States Patent Office.

SIMEON TAYLOR, OF WORCESTER, MASSACHUSETTS.

Design No. 3,507, dated May 25, 1869.

DESIGN FOR THE DOOR OF A BOOK-CASE.

The Schedule referred to in these Letters Patent and making part of the same.

Know all men by these presents:

That I, SIMEON TAYLOR, of the city and county of Worcester, and Commonwealth of Massachusetts, have originated a new Design for Doors for Library-Cases, of which the following is a full, clear, and exact description, reference being had to the accompanying drawing, making a part of this specification.

In the drawing—

A represents the outer or skeleton-frame of the door, which may be made of any desired material, and ornamented with scrolls or other carved work, B.

The centre of the door is filled with a series of imitation pipes, 1, 2, 3, 4, similar to or resembling those

ordinarily applied to the front of an organ, as fully shown in the drawings.

A library-case door thus made is quite ornamental, thus adding very much to the appearance of the piece of furniture.

What I claim as my invention, and desire to secure by Letters Patent, is—

The design for a library-case door, as herein described, and as shown in the accompanying drawing.

SIMEON TAYLOR.
